UNITED STATES PATENT OFFICE

1,974,576

REFLECTOR SIGN

Richard W. Luce, Westfield, N. J., assignor to
 Signal Service Corporation, a corporation of
 Delaware

Application August 16, 1933, Serial No. 685,428

7 Claims. (Cl. 88—1)

This invention relates particularly to the mounting of reflector buttons in sign plates or boards of natural or artificial wood or like fibrous material which can be readily pierced with a sharp 5 instrument.

In accordance with this invention the button employed has a limiting circumferential flange or collar near its front end and the button body is of a size to enter a hole bored in the face of 10 the mounting until the flange or collar strikes the outer face of the mounting. The body is provided however, with protuberances such as sharp barbs, for example, which extend beyond the wall of the hole and pierce the material. As the button is forced in by pressure against its outer end, 15 the protuberances bite into or pierce the wall and secure the button in the hole.

When barbs are used they will preferably be inclined to the axis so as to have a spiral disposition and thus cause the button to rotate as it is forced into the hole, the barbs describing a spiral path in the wall. Preliminarily the wall will 20 preferably be treated to seal the pores and exclude moisture. The barbs will most conveniently be formed on a separate clip applied to the button.

I shall now describe the illustrated embodiment of the invention and shall thereafter point out my invention in claims.

30 Fig. 1 is a cross section through a button receiving hole in a sign board mounting with a button shown in place and with a mounting tool immediately above the button.

Fig. 2 is a plan of the barb carrying clip shown 35 applied to the button in Figure 1.

Fig. 3 is a side elevation of the clip.

Fig. 4 is a view similar to Figure 1 showing a slightly modified form of mounting.

In the form of mounting shown in Figure 1, the 40 board 1 has a cylindrical hole 2 bored therein, of a size to receive the body of the button 3 with a fairly tight fit. The hole is first treated with shellac or paint to seal the pores of the wood and keep out moisture. The flange 3a on the front 45 end of the button is of a size to abut against the front face of the mounting and thus provide an overlap to seal the opening.

At the bottom of the cylindrical wall of the button body are provided two diametrically opposite securing lugs 3b and 3c. On these there 50 is secured the clip 4 shown in detail in Figures 2 and 3. This clip is of sheet metal and has a bottom plate portion 4a with arcuate ends and upstanding from the ends are the arcuate flanges 4b and 4c, one at each end. These flanges are

provided with a hole or recess which receives and interlocks with the respective securing lug 3b or 3c. Thus the clip is locked on to the body.

One corner of each flange 4b and 4c is bent back to form a barb, the two barbs being formed 60 on corresponding corners of the flanges and being substantially equally inclined to the axis of the button so as to have a spiral relation. The barbs are numbered respectively 4b' and 4c' and they extend well beyond the wall of the hole when the 65 button is centrally disposed therein. Consequently they pierce into the wood and securely hold the button in place against any pulling force which can ordinarily be applied to the outer end 70 of the button.

To insert the button a tool 5 such as shown in Figure 1 may be used. This has a socket of a size and shape to receive the end of the button with the peripheral edge resting on the flange 3a. Mallet blows on the outer end of the 75 tool so set will drive the button into its hole and cause the barbs to cut a path along the wall. Since the barbs are spirally disposed they will traverse a spiral path as the button is forced longitudinally. In other words the button as a 80 whole will rotate as it descends.

Where it is desired to recover the button after a short period of use, the hole in the mounting should be drilled entirely through as shown at 85 2a in Figure 4, and a back plate 1a placed over the rear of the sign plate as shown. To recover the reflector the back plate is removed and the reflector may be driven out from the rear with a flat faced tool without any injury to the 90 reflector.

It is obvious that the construction illustrated and described can be otherwise variously modified without departing from the spirit or scope of the invention as expressed in the appended 95 claims.

I claim:

1. A sign construction comprising a mounting of fibrous material having a button receiving hole in one face thereof, a reflector button the body of which is entered into said hole, and sharp pointed barbs spirally disposed on the body extending outwardly beyond the wall of the hole into the material of the mounting. 100

2. A sign construction comprising a mounting of fibrous material having a button receiving 105 hole in one face thereof, a reflector button the body of which is entered into said hole, and a clip secured on the body and provided with a plurality of barbs inclined to the axis in the same direction and having their ends extending into

the material of the mounting in retaining relation.

3. A sign construction comprising a mounting of fibrous material having a button receiving hole in one face thereof, a reflector button the body of which is entered into said hole, and a clip secured upon the inner end of the body and having two opposed outwardly turned barbs inclined to the axis in the same direction so as to cause the button to move spirally as it is forced into the hole, the ends of the barbs having their ends extending into the material of the mounting in retaining position.
4. A sign comprising a wooden sign board having a button receiving hole in one face, a reflector button the body of which is inserted into the hole, and a clip locked to the inner end of the body and having two opposing arcuate flange portions disposed circumferentially of the body, corresponding corners of the flange portions being bent out so as to form spirally disposed barbs the ends of which extend into the wooden wall of the hole and hold the button in the hole.

5. A sign construction comprising a mounting having a button receiving hole in one face thereof, a reflector button the body of which is entered into said hole, and a clip secured on the body and provided with an element driven into the material of the mounting in retaining relation.

6. For signs the symbols of which are defined by reflector buttons set into holes provided in a support therefor, a reflector button, a clip therefor including an element adapted to pierce the support and secure the clip thereto, and means for securing the reflector button to the clip.

7. For signs the symbols of which are defined by reflector buttons set into holes provided in a support therefor, a reflector button, a clip therefor including barbs adapted to pierce the support and secure the clip thereto, and complementary interlocking projections and recesses on the button and clip for securing the button to the clip.
